John Hibell.

United States Patent Office.

JOHN HIBELL, OF NECHELLS, ENGLAND.

Letters Patent No. 79,759, dated July 7, 1868.

IMPROVEMENT IN ANNEALING-POTS AND SAUCERS.

The Schedule referred to in these Letters Patent and making part of the same.

TO ALL TO WHOM IT MAY CONCERN:

Be it known that I, JOHN HIBELL, of Nechells, near Birmingham, in the county of Warwick, England, wire-drawer, a subject of the Queen of Great Britain, have invented or discovered new and useful "Improvements in Annealing-Pots and Saucers, for Annealing Iron and Steel Wire, Sheet Metal, and other articles;" and I, the said JOHN HIBELL, do hereby declare the nature of the said invention, and in what manner the same is to be performed, to be particularly described and ascertained in and by the following statement thereof; that is to say—

Annealing-pots as ordinarily constructed consist of hollow cylinders of cast iron, closed at bottom, and furnished with a lid or cover at top, which lid is closed nearly air-tight during the annealing process. The said pots are built in a furnace, and are charged with the articles to be annealed, and heated to the required degree. By annealing iron and steel wire and other articles in pots of this kind, the surfaces of the said articles are more or less covered with scale produced by the presence of air in the said pots.

The object of my invention is to anneal articles so as to avoid the production of scale on their surfaces, or to reduce it to a minimum, as well as to heat the annealing-pot rapidly and uniformly.

In constructing annealing-pots according to my invention, I make them of two hollow cylinders of cast iron of different diameters, the inner or smaller hollow cylinder being situated concentrically within the outer or larger hollow cylinder. An annular or ring-like space is thus left between the two hollow cylinders, which space constitutes the chamber in which the articles to be annealed are placed. The bottom of the said chamber is closed, and the top is also temporarily closed, during the annealing process, by a lid or cover, which lid or cover is made air-tight in any convenient way. The interior of the pot, that is, the space within the small hollow cylinder, is open, so that all parts of the said pot are exposed to the action of the heat in the heated annealing-pot, or furnace, or muffle.

In using the annealing-pot for annealing iron or steel wire, the bundles of wire are charged into the annular space in the pot, the said bundles of wire filling up the said space. The air-space thus left in the said pot is very small, and the oxidation or scaling of the surface of the wire during the annealing process is wholly or mainly prevented. By exposing the inside of the pot, as well as the outside, to the action of the heat, the wire is more readily and uniformly heated than when the pot is heated from the outside only.

When sheet metal is to be annealed in pots constructed according to my invention, it is coiled into rings or bands, of a diameter equal to that of the annular space of the pot, and the said rings charged into the said pot. When small articles are to be annealed, I reduce the annular space in which they are placed, so as to anneal them in contact with as little air as possible.

By the use of my invention, the production of scale on the articles annealed is wholly prevented, or reduced to a minimum, and the cleaning or pickling process, which is necessary to remove the scale produced by the ordinary method of annealing, is thus in a great measure rendered unnecessary.

My invention consists further in the following improvement or improvements in the saucers on which annealing-pots are supported in the furnace. In addition to the ordinary low cylindrical flange of the said saucers, I make another cylindrical flange, external to the ordinary one, and concentric therewith, the said additional flange extending from one-third to one-half the height of the pot. The said additional flange may either be made of cast iron or brick-work. By the use of the said additional flange the fire is prevented from injuriously affecting the bottom of the annealing-pot, and the pot so protected lasts longer than pots set upon saucers of the ordinary kind.

This part of my invention may be applied to pots of the ordinary kind, as well as to pots constructed according to my invention. In the latter case I prefer to use a flange, both within and without the pot, for protecting the bottom from the action of the fire.

Having explained the nature of my invention, I will proceed to describe, with reference to the accompanying drawing, the manner in which the same is to be performed.

Figure 1 represents in elevation an annealing-pot constructed according to my invention.

Figure 2 is a vertical section of the same, and

Figure 3 is a plan of the same.

The same letters of reference are employed to indicate the same parts in the several figures of the drawing.

a b are the two hollow cylinders of cast iron, constituting the annealing-pot. The said hollow cylinders are of different diameters, the inner or smaller one, *b*, being situated concentrically within the outer or larger one, *a*, as represented. Each of the said cylinders *a b* is expanded at top, for the purpose of forming a support or bed for the lid or cover of the pot. Between the two hollow cylinders *a* and *b*, an annular or ring-like space, marked *c*, is left, which space constitutes the chamber in which the articles to be annealed are placed. The bottom of the chamber *c* is closed at *d*, and the top of the said chamber is open, but the said open top is temporarily closed during the annealing process by a lid or cover of a ring-like form. This lid or cover is shown separately in section in Figure 6, and is marked *e*. The said lid or cover *e* has upon its bottom, V-shaped annular projections, *e²*, which fit in V-shaped annular grooves or depressions, *e³*, in the enlarged top of the annealing-pot.

The lid or cover *e*, fitted on the top of an annealing-pot, is represented in Figure 5. By means of the V-shaped projections and depressions, the lid or cover *e* is made air-tight; or the said lid or cover may be made air-tight by a sand-joint, or in any other convenient way. I prefer to make the inner hollow cylinder, *b*, of the annealing-pot slightly conical, as represented in the drawing, but the sides of the hollow cylinder may be parallel. The central hollow space, *f*, within the small or inner hollow cylinder, *b*, is open both at top and bottom, for the circulation of heated air through the said space, so that all parts of the pot are exposed to the action of the fire and heat in the heated annealing-pot, or furnace, or muffle, and the articles to be annealed, are thus more rapidly and uniformly heated than when the pot is heated from the outside only.

In annealing iron or steel wire, the circular bundles of wire are charged into the annular annealing-chamber *c* of the pot, the said bundles of wire filling up the said chamber. The air-space thus left in the pot is very small, and the oxidation or scaling of the surface of the wire during the annealing process is wholly or mainly prevented. The bundles of wire charged into the chamber *c* are exposed on their inner and outer sides to the action of the heated inner and outer sides of the annealing-pot, and the said bundles are thereby rapidly and uniformly annealed.

In annealing sheet metal, it is coiled into rings or bands of a diameter equal to that of the annular chamber *c* of the pot, and the said rings are charged into the pot in a manner similar to that of the wire bundles. Any kind of wire or metallic rods, or other large articles capable of being coiled into a ring-like figure, and requiring to be annealed, may be charged into the annealing-pot in the same manner.

When small articles are to be annealed, they may be placed in the annealing-pot without being bent. In annealing small articles, I prefer to employ a small annealing-pot, but I do not limit myself to any particular size of the annealing-chamber in which the articles are annealed.

When it is desired to prevent to the utmost the oxidation of the wire or articles being annealed, I separate the pot into several chambers by means of the movable intermediate lids, *p p*, fig. 5.

Instead of making the smaller hollow cylinder *b* of the pot open at top and bottom, as in the annealing-pot represented in figs. 1, 2, and 3, the said small cylinder may be closed at bottom and open at top, as represented in the vertical section of the annealing-pot, Figure 4, or the said small cylinder may be closed at top and open at bottom, as represented in the vertical section of the annealing-pot, fig. 5. In both these cases the inner side of the annealing-chamber *c* of the pots is exposed to the heated air of the annealing-furnace or muffle; but the said heated air does not circulate through the cylindrical opening in the middle of the pot, as in the arrangement represented in figs. 1, 2, and 3.

In using annealing-pots made according to my invention, I remove them from the muffle or furnace in which they are heated, as soon as the contents of the said pots are sufficiently hot, and allow the said pots and their contents to cool in the air. I charge other pots, filled with wire or articles to be annealed, into the heated muffle or furnace, and so on, so as to avoid the loss of heat which is incurred when the pot is built in the furnace, and the furnace allowed to cool with the pot. Two or more of my improved pots may be placed one upon the other, in the furnace or muffle.

My improved annealing-pots may be built in the furnace when preferred.

Annealing-pots made according to my invention may be cast in one piece, or they may be made in two or more pieces, bolted or otherwise connected together.

Figure 7 represents, in elevation, and

Figure 8 in vertical section, a saucer for supporting annealing-pots, made according to my invention, in the furnace or muffle in which they are heated.

Figure 9 represents the said saucer in connection with an annealing-pot of the construction represented in fig. 2. The said saucer consists of two cylindrical flanges, *g h*, concentric with one another, the said flanges being connected to or made in one piece, with the base, *i*. When the pot is placed in the saucer, the flanges *g h* are situated on the inner and outer sides of the said pot. The said flanges *g h* may extend from one-third to one-half the height of the pot, and they may either be made of cast iron or of brick-work. By the use of the said flanges *g h*, the fire is prevented from injuring the bottom of the annealing-pot both on its outer and inner sides, and the pot so protected lasts longer than if set upon a saucer of the ordinary kind.

Figure 10 represents a saucer for supporting ordinary annealing-pots made according to my invention. *k* is the ordinary flange of the saucer *l*, and *m* is the additional cylindrical flange, concentric with and external to the said ordinary flange *k*. *n* is the annealing-pot set upon the saucer *l*. The said additional flange *m* may

extend from one-third to one-half the height of the pot, the said additional flange protecting the bottom of the pot from the action of the fire.

Although annealing-pots made according to my invention are especially applicable to the annealing of iron and steel wire, yet the said pots may also be used advantageously for annealing all such metallic sheets and wires and other metallic things as require to be annealed.

Having now described the nature of my said invention, and the manner in which the same is to be performed, I wish it to be understood that I do not limit myself to the precise details herein described and represented in the drawing, as the same may be varied without departing from the nature of my invention; but

I claim as my invention—

1. The improvements in annealing-pots for annealing iron and steel wire, sheet metal, and other articles hereinbefore described, and illustrated in the accompanying drawing; that is to say, making the said annealing-pots of two concentric hollow cylinders, of different diameters, the space between the said hollow cylinders constituting an annular chamber, in which the articles to be annealed are placed, the said annular chamber being exposed to the fire and heat, both on its outer and inner sides, substantially as described and illustrated.

2. The improvement or improvements in the saucers used for supporting annealing-pots in the furnaces or muffles in which they are heated, hereinbefore described, and illustrated in the accompanying drawing; that is to say, making the said saucers with a double flange, by means of which the bottom of the annealing-pot is protected from the injurious action of the fire, substantially as described and represented.
